BOTTLE CAPPING MACHINE

Filed Feb. 9, 1927

FIG. 1

INVENTOR.
William F. Bradley,
BY Walter N. Haskell.
his ATTORNEY.

UNITED STATES PATENT OFFICE

WILLIAM F. BRADLEY, OF ROCK ISLAND, ILLINOIS

BOTTLE-CAPPING MACHINE

Application filed February 9, 1927. Serial No. 166,835.

My invention has reference to a bottle-capping machine, of that type which is employed for placing the crowns or caps on the tops of bottles containing various kinds 5 of beverages. One of the purposes thereof is to provide a machine having adjustment features permitting its use over a considerable range of sizes and heights of bottles.

Another object thereof is to have the capping die rigidly supported and operating on a vertical line, so that the danger of breakage of bottles during the capping operation is eliminated.

Another purpose thereof is to provide 15 means for the quick adjustment of the capping head to accommodate the same to bottles of varying heights, without the manipulation of any bolts or screws, or the loss of any time.

Another object of the invention is to provide 20 means for compelling a quick return of the capping head, and parts connected therewith, immediately following the capping operation. Coupled therewith is an automatic release mechanism which aids in separating the cap from the capping die. This latter mechanism is also capable of being adjusted, so as to adapt it perfectly to its work.

The above-named, and other features and 30 advantages of the invention will more fully appear from the following specification, taken in connection with the accompanying drawings, in which:

Fig. 1 shows the device in side elevation.

Fig. 2 is a cross-section thru the upper 35 part of the frame and capping devices thereon.

Fig. 3 shows the base and lower part of the frame in front elevation, in reduced 40 size.

The invention is provided with a support, formed of a base 1, having a raised edge 2, and a frame 3 of double formation, connected 45 with plates 4 fixed to the base, said base and frame being adapted to receive bottles of varying sizes. Said frame is projected upwardly into standards 5 and 6, spaced apart and united near their rear edges by a web 6^a. The other edges of said standards 50 are provided with coinciding pairs of

notches 7, to receive a pin 8, upon which is fulcrumed a hand-lever 9.

Movable vertically on the standards is a slide 10, to which is attached a frame 11, which frame is connected with the hand-lever 9 by a pair of links 12, pivoted at their upper ends on a pin 13 in said hand-lever, and at their lower ends on a pin 14, held in the frame 11. Fixed to the lower end of the frame 11 is a capping die 15, of suitable size and shape to set a crown on the upper end of a bottle supported in the machine, as indicated at 16. This is done by establishing the capping mechanism on the standards so that the capper will be just 55 above the top of the bottle, with the lever 9 in a substantially horizontal position. A limited downward movement on said lever will then operate to fix the cap firmly in place. In the capping operation the pins 60 13 and 14 are in a substantially vertical alignment, so that the force of the lever 9 is exerted in a straight downward direction, with better results than if such force were to be exerted from the side. 75

The lever 9 is held normally in an elevated position, and is returned thereto after having been lowered, by means of a coiled spring 17, connecting the pin 8 with a screw 18 in the slide 10. In the downward movement of the lever the spring is considerably extended, increasing the tension thereof, which operates to disengage the capping head quickly from the bottle. The action of the spring also moves the slide 10 upwardly 80 on the standard. The disengaging movement is aided by means of a stem 19 and plunger 20 on the lower end thereof, within the die 15. A slot 21 permits vertical movement of said stem on the pin 14, and the upper end of said stem is connected with the pin 13 by means of a slot 22. Said stem is provided with a shoulder 23, between which and the pin 13 is interposed a coiled spring 24, which spring is compressed upon the 85 downward movement of the lever 9. In the capping operation the disk 20 is forced upwardly in the die 15, after which the stem 19 is held firmly while the handle 9 moves downwardly with relation thereto, compress- 90 95 100

ing the spring 24 between the pin 13 and shoulder 23. As soon as the pressure of the handle is relieved, the force of the spring 24, exerted downwardly upon the stem 19 and disk 20, aids in expelling the cap and end of the bottle from the die 15. On account of the rigid connection of the die 15 with the frame 11, and the positive movement of such frame in a direct vertical line, there is no possibility of any variation of the movement of the die from the same vertical course, and if the bottle which is being capped is properly positioned on the base 1 there is no danger of breakage thereof while receiving the capping pressure.

The hand-lever 9 is capable of a rocking movement on the pin 14, and by holding the slide 10 with one hand and forcing the lever forwardly with the other the pin 8 is disconnected from the pair of notches in which it is seated and the lever and slide can then be freely moved upwardly or downwardly on the standard, and the pin re-engaged with another pair of notches, after the desired adjustment has been made. In ordinary use the machine would be employed for a considerable time with one size of bottles, so as to require no adjustment, but it will be evident that if there is a change in the size of the bottles to be capped, it is only the work of an instant to make the required change in the machine. In the rocking movement of the lever 9 the stem 19 is also tipped to one side a little, and the opening for the passage of said stem in the upper part of the die 15 is sufficiently large to permit of such movement.

The spring 24 is provided with a sufficient amount of compressive force, but if for any reason it should be less than desired such defect may be remedied by the insertion of one or more washers between the end of the spring and shoulder 23, as shown at 25.

The handle 9 is also of double formation and has a pair of parallel end plates thru which the pin 8 passes.

What I claim, and desire to secure by Letters Patent, is:

1. In a device of the class described, a frame and standard support thereon provided with a series of notches, a capping head slidable on said standard and provided with a bottle-capping tool, a lever having a rocking connection with said head and provided in one of its ends with a pin for engagement with said notches, and a spring connection between said pin and head, returning said head and lever to a raised position after being lowered.

2. In a device of the class described, a frame and standard thereon, provided in one of its edges with a series of detents, a slide on said standard, a capping device rigidly attached thereto, a lever having a rocking connection with said slide, a detent key in one

end of said lever for alternative connection with said detents, an ejector in said capping device, a stem connecting said ejector with said lever, and compression devices on said stem, receiving tension in the capping operation.

3. In a device of the class described, a frame and standard thereon, provided in one of its edges with a series of detents, a slide on said standard, a capping device rigidly attached thereto, a lever having a rocking connection with said slide, and a detent key in one end of said lever for alternative connection with said detents, an ejector in said capping device, a stem connecting the said ejector with said lever, compression devices on said stem, receiving tension in the capping operation, and means for adjustment of said tension.

4. In a device of the class described, a frame and support thereon, provided with a series of notches, a slide movable on said support, a capping device connected therewith, a lever having a link connection with said slide, and provided with a pivot pin engageable with said notches, a spring connecting said pin and slide, tending to move the slide upwardly, and a spring-actuated ejector in said capping device, aiding in the separation of the bottle and capping device.

5. A device of the class described, comprising a bottle receiving frame, spaced-apart standards mounted thereon and provided with series of notches, a slide movable on said standards and provided with a bottle capper support, a bottle capper rigidly attached to said support, a lever having a pin in one of its ends for selective engagement with said notches, links connecting said lever with said slide permitting a rocking movement to the lever, a spring connection between said lever and said slide, an ejector in said bottle capper having a stem therefor connected with said lever, and a compression device between said lever and ejector, receiving tension from the capping operation.

In testimony whereof I affix my signature.

WILLIAM F. BRADLEY.
